JACK STRAP AND CLAMP FOR LOOMS

John Allen Roach, Lanett, Ala., assignor to
William D. Dodenhoff, Greenville, S. C.

Application November 14, 1945, Serial No. 628,395

6 Claims. (Cl. 139—88)

1

The present invention relates to an improved type of adjustable jack strap for lifting and lowering the heddle frames of the shedding mechanisms of looms or the like, where a more or less delicate adjustment is desired.

In the accompanying drawing:

Fig. 1 is a perspective view of one end of the jack strap, with the strap shown in cross-section;

Fig. 2 is a detached perspective view of the clamp parts; and

Fig. 3 is a detached plan view of the strap.

The jack strap 1 is provided at one of its ends at least, with a loop 2 which is connected to and is coupled between the heddle frame and the jack lever which operates the heddle frame. The one end of the strap 1 is folded upon itself, as at 3, to provide a plurality of layers 1a and 1b adjacent the body portion 1 of the strap. The body portion, beyond the loop 2, is longitudinally slotted at 4 to provide for said adjustment.

A pair of identical clamp plates 5, 5 are reversed with respect to each other and placed on the body 1 and fold 3 with a clamp bolt 6 passing through holes 7, 7 in the plates 5, 5, through similar aligned holes 14, 14 (Fig. 4) in the plies 1a and 1b of the fold 3 and through the slot 4 in the body 1 of the strap, with the head 8 of said bolt bearing on one of the plates 5, a washer 9 on the other of the plates 5, and a butterfly nut 10 screwed on the threads of the bolt 6 and adapted, when tightened, to clamp the folded end 3 of the strap tightly against the body 1 of the strap, while providing for delicate adjustment therebetween merely by loosening the nut 10 and sliding the folded end relative to the body 1 to increase or decrease the size of the loop 2.

The plates 5, 5 are provided at one end or side with a single centrally located right-angle ear 11 and along the opposite end or side with a pair of laterally-spaced right-angle ears 12, 12 between which the body 1 and folded end 3 of the strap lie to keep the longitudinal side edges of the layers 1a, 1b of the folded end 3 and the corresponding edges of the body 1 of the strap in alignment and parallel.

I claim:

1. A jack strap and clamp for looms, comprising a flat strap folded to form a loop and superposed layers adjacent said loop at one end with an elongated slot in said strap and aligned bolt holes in said layers, a pair of flat clamp plates including opposed flat surfaces extending uninterruptedly from side to side thereof in opposed relation on opposite faces of said strap and layers,

a clamp bolt passing through aligned apertures in said plates and said layers and said slot and adapted to clamp said strap and said layers tightly between said surfaces in frictional contact with each other and said surfaces of said plates, and means on the opposite ends of each plate and overlying the longitudinal edges of said strap and said layers for maintaining parallel alignment thereof.

10. 2. A jack strap and clamp for looms, comprising a flat strap folded to form a loop and superposed layers adjacent said loop at one end with an elongated slot in said strap and aligned bolt holes in said layers, a pair of flat clamp plates including opposed flat surfaces extending uninterruptedly from side to side thereof in opposed relation on opposite faces of said strap and layers, a clamp bolt passing through aligned apertures in said plate and said layers and said slot and adapted to clamp said strap and said layers tightly between said surfaces in frictional contact with each other and said surfaces of said plates, and interfitting means on the opposite ends respectively of said plates and overlying the longitudinal edges of said strap and said layers for maintaining parallel alignment thereof.

30. 3. A jack strap and clamp for looms, comprising a flat strap folded to form a loop and superposed layers adjacent said loop at one end with an elongated slot in said strap and aligned bolt holes in said layers, a pair of identical and reversible flat clamp plates including opposed flat surfaces extending uninterruptedly from side to side thereof in opposed relation on opposite faces of said strap and layers, a clamp bolt passing through aligned apertures in said plates and said layers and said slot and adapted to clamp said strap and said layers tightly between said surfaces in frictional contact with each other and said surfaces of said plates, and means on the opposite ends of each plate and overlying the longitudinal edges of said strap and said layers for maintaining parallel alignment thereof.

40. 4. A jack strap and clamp for looms, comprising a flat strap folded to form a loop and superposed layers adjacent said loop at one end with an elongated slot in said strap and aligned bolt holes in said layers, a pair of identical and reversible flat clamp plates including opposed flat surfaces extending uninterruptedly from side to side thereof in opposed relation on opposite faces of said strap and layers, a clamp bolt passing through aligned apertures in said plates and said layers and said slot and adapted to clamp said

strap and said layers tightly between said surfaces in frictional contact with each other and said surfaces of said plates, and interfitting means on the opposite ends respectively of said plates and overlying the longitudinal edges of said strap and said layers for maintaining parallel alignment thereof.

5. A jack strap and clamp for looms, comprising a flat strap folded to form a loop and superposed layers adjacent said loop at one end with an elongated slot in said strap and aligned bolt holes in said layers, a pair of flat clamp plates including opposed flat surfaces extending uninterruptedly from side to side thereof in opposed relation on opposite faces of said strap and layers, and a pair of ears on the opposite ends respectively of said plates and extending from said plates substantially at right angles to the planes of said plates for overlying the longitudinal edges of said strap and said layers for maintaining parallel alignment thereof.

10. A jack strap and clamp for looms, comprising a flat strap folded to form a loop and superposed layers adjacent said loop at one end with

an elongated slot in said strap and aligned bolt holes in said layers, a pair of flat clamp plates including opposed flat surfaces extending uninterruptedly from side to side thereof in opposed relation on opposite faces of said strap and layers, a clamp bolt passing through aligned apertures in said plates and said layers and said slot and adapted to clamp said strap and said layers tightly between said surfaces in frictional contact with each other and said surfaces of said plates, a pair of laterally spaced ears on one end of each clamp plate and a single central ear on the opposite end thereof adapted to be reversed and interfitting in the assembled strap and clamp for maintaining parallel alignment of the longitudinal edges of said strap and layers clamped by and between said plates and between said interfitted ears thereof.

15. A jack strap and clamp for looms, comprising a flat strap folded to form a loop and superposed layers adjacent said loop at one end with
